UNITED STATES PATENT OFFICE.

CHESTER W. CANINE, OF DES MOINES, IOWA.

MARKING-MACHINE FOR LAUNDRY ARTICLES.

No. 830,567.

Specification of Letters Patent.

Patented Sept. 11, 1906.

Application filed June 23, 1905. Serial No. 266,629.

To all whom it may concern:

Be it known that I, CHESTER W. CANINE, a citizen of the United States, residing in Des Moines, county of Polk, State of Iowa, have 5 invented certain new and useful Improvements in Marking-Machines for Laundry Articles, of which the following is a full, clear, and exact description, reference being had to the accompanying drawings, forming part of 10 this specification.

My improvements relate to machines for marking laundry articles of the kind shown and described in my pending application for Letters Patent, Serial No. 147,540, filed 15 March 12, 1903, in which a plurality of groups of type wheels or bars are provided, one type-wheel of each group having a corresponding type-wheel in each other group and bearing a similar but different-sized 20 type, the similar but different-sized type of each group being selected simultaneously by the actuation of a set of keys, one set for corresponding type-wheels of each group, whereby by means of intermediate mechanism the 25 selected group of type of the various sizes are brought into position for proper operating-platen to impress the mark selected on the laundry goods, the size of type being selected to suit the kind of goods to be marked. 30 It is the purpose of my present invention to simplify my former construction, to avoid as much as possible a multiplicity of parts, and to economize space in the arrangement of same, to prevent any change of the selected 35 mark by the careless or accidental operation of the keys after the proper type have been set, and in many other respects to be hereinafter particularly pointed out and claimed to improve the mechanical construction and operation of the machine.

In the drawings, Figure 1 is a top plan view of the machine. Fig. 2 is a front elevation. Fig. 3 is a sectional side elevation taken on lines 3 3 of Fig. 2. Fig. 4 is a sectional front elevation of the upper portion of 45 the machine, taken just within the front wall. Fig. 5 is a sectional side elevation taken just within the side wall. Fig. 6 is a detail side elevation of the operating devices for the 50 printing mechanism. Fig. 7 is a detail section of the inking device.

1 is the base-plate, 2 3 the side walls, and 4 5 the front and rear walls of the casing to hold the operating parts. The machine 55 itself may be secured upon a suitable table or

be provided with standards for a supporting-frame to present the machine at the proper height for convenient operation. I have, however, not considered it necessary to illustrate such support.

Slidably mounted in the top plate 6 of the casing, which is suitably stepped for the purpose, are a series of groups of keys 7, 8, 9, and 10, (four groups in the present instance,) severally lettered and numbered with the 60 letters of the alphabet and numerals from "0" to "9." These keys are pivotally secured by the vertical rods 11, 12, 13, and 14 to horizontally-disposed key-levers 15, 16, 17, and 18, arranged in banks and pivoted at the 65 rear end on rods 19, 20, 21, and 22, which have their support in the side walls of the casing. Vertically depending from each key-lever 15 16 17 18 of each bank are the rods 23, 24, 25, and 26, which slide vertically and 70 are guided through slots in the fixed plates 27, 28, 29, and 30, which are secured in horizontal position to the side walls of the casing, while to serve also as a suitable guide for the lower banks of key-levers the plates 27, 28, 75 29 are provided with vertical flanges 30, 31, and 32, which are slotted to receive the key-levers when actuated, the base of the slot forming a slot for the levers, while a slotted plate 33 also depends vertically from the 80 casing-top to serve as a guide for the uppermost bank of key-levers. Coiled springs 34, 35, 36, and 37 are mounted on the several rods 23, 24, 25, and 26, which have their bearing between the key-levers and the 85 guide-plates 27, 28, 29, and 30 to return the 90 key-levers and keys to their normal position when released, as hereinafter described.

The banks of key-levers are provided with locking-bars 39, 40, 41, and 42, one for each 95 bank, which extends horizontally across the front ends of the respective levers of each bank and are supported at the ends by spring-arms 43, 44, 45, and 46, suitably secured to the side casing. These locking-bars are bevelled to correspond with the corresponding bevel on the front abutting ends of the respective sets of key-levers, and the spring-arms tend to throw the locking-bars inward, so that when any of the key-levers are depressed 100 the locking-bar will be pressed back to allow the key-lever to pass and then returning to normal position will hold in depressed position any key-levers that may have been actuated until released by means 105 110

of the releasing-key 47, which is coupled to the horizontal lever 48, pivoted to the side wall of the casing. 49, 50, 51, and 52 are bell-crank levers mounted, respectively, on 5 the key-lever rods 19, 20, 21, and 22, connected, respectively, by connecting-rods 53, 54, 55, and 56, pivoted to the horizontal arms of the bell-crank with the lever 48, while the vertical arms of the bell-crank levers are connected by the bars 57, 58, 59, and 60 with the respective locking-bars 39, 40, 41, and 42. It will be evident from this construction that when the releasing-key lever 47 is depressed all of the locking-bars will be moved back to 15 allow the coiled springs 34, 35, 36, and 37 to return to normal position any keys that may have been depressed and which have been held down by the locking-bars, the releasing-key being itself returned to normal by the 20 turn of the locking-bars to normal position.

Mounted horizontally underneath each bank of key-levers and suitably journaled in the side walls of the casing so as to rotate are the type-setting cylinders 61, 62, 63, and 64, 25 one for each bank of key-levers, extending lengthwise under all of the rods 23, 24, 25, and 26 thereof. The normal upper portions of these cylinders are solid throughout their length, and the rods 23, 24, 25, and 26 extend 30 very close to this surface, so that in normal position none of the keys can be actuated. From this uniform solid portion the cylindrical surface of the cylinders is notched or cut away spirally in steps, as indicated at 65 in 35 Fig. 4, the several steps corresponding to the letters and numerals of the several banks of keys. The type-setting cylinders are each connected by their several chains 66, 67, 68, and 69 or other flexible connections, each 40 with its respective sheave or drum 72, keyed to a horizontal shaft 70, journaled at the back in the side walls of the casing, which shaft and the drums or sheaves are rotated by the hand-crank 71 outside of the casing. The 45 effect of the rotating or winding up of the drums 72 is to rotate the several type-setting cylinders in the direction of the arrows shown in Fig. 3. For the upper cylinder the rotation is in one direction, while for the other 50 three cylinders it is in the opposite direction, because in one case, merely to prevent the chains interfering with other working parts, the connection with the cylinder is above, while for the others it is below. It is entirely immaterial, however, in which direction the cylinders rotate. Upon the several 55 cylinder-shafts are mounted coiled springs 73, one end secured to the cylinder and the other to the casing, so that the rotation of 60 the cylinder is against the force of the spring which tends to rotate the cylinder back to its normal position. In order to economize pace, the chains running from two of the cylinders are secured at one end of their respective cylinders and for the other cylinders at 65

the other end, while the coiled springs 73 are secured at the opposite end from the chain connection.

When the hand-crank 71 is actuated as above set forth, all of the cylinders are rotated, so that the open portions are under the key-lever rods, and any of the key-levers can then be depressed and held down by the locking-bar, so that the end of the key-rod will project into the pathway of the stepped 75 spirally-arranged notches on the cylinder, and the respective cylinders will be stopped in their return by the projecting key-rod and at a different place for each key, it being understood that only one key is actuated in 80 each of the four groups of keys.

Keyed on each end of each cylinder-shaft are the gear-wheels 74 74, 75 75, 76 76, and 77 77, which mesh, respectively, with gears on the type-wheels 78 78, 79 79, 80 80, and 81 81, 85 which are mounted loosely in the shaft 82, horizontally disposed and secured in the side walls of the casing. These type-wheels are provided on their peripheries with type to correspond to the numbered and lettered keys, 90 and the corresponding type-wheels at each end of the shaft 82 are similar, except that the type are of different size. Only two sets of type-wheels of different-sized type are shown in the present machine; but it will be readily 95 understood that by adding addition gears on the cylinder-shafts and additional type-wheels on the type-wheel shaft 82 as many sets of type-wheels of different-sized type may be provided as desired. The rotation of the 100 type-setting cylinders, it will be seen, controls, through the gearing, the amount of rotation of the respective type-wheels geared thereto, and the type-wheels are so arranged that the type to correspond with the key operated will be presented at the printing position at the openings 83 83 in front of the case. The groups of type-wheels are all mounted on the same shaft and the respective type of each group are brought close together in alignment at the printing position. The arrangement of type-setting cylinders each geared to its wheel of different-sized type for the several groups enables me to conveniently dispose the cylinders in the case so as to economize 115 space. Should any of the type-setting cylinders be located too far away to be geared directly with the type-wheels, intermediate gear can be employed, as is the case in the present machine, the intermediate gear 84 120 being employed to connect the cylinder-gear 77 with the type-wheels 81.

In order to print the desired mark on the goods, the article is held on the printing-surface 83, and the platen-lever 85, with its platen-plate 86, pressed against the article to force it upon the type, either printing-lever being selected in accordance with the size of type desired.

The printing-levers 85 86 are pivoted in 130

arms 87 88, depending from the casing, and each lever carries an arm 89, coupled at the rear by connecting-rod 90, and arm 91 with a rock - shaft 92. This rock - shaft carries at each end a segmental hook-plate 93, pivoted at the end of the rock-shaft arm 91 and coupled at the rear by a coiled spring 94, with the nose 95, on the rock-shaft. The hook 96 of this hook-plate 93 engages a roller-pin 97 on the lower end of the lever 98, pivoted near its center on the casing. A segment-rack 99 is formed on the upper end of this lever 98, which engages the teeth 100 on the curved inner end of the inking-bar 101. The lower end of this inking-bar is slotted at 102 and is mounted in the shaft 103, supported in the casing. The inking-bar carries at its outer end the inking-pad 104, which receives its ink from the pad 105, pivotally mounted in the casing and provided with a projection 106, against which the end of the inking-bar bears to keep the two pads in close contact. As the platen-lever 85 is pushed toward the machine (and it will be understood that there are as many platen-levers, inking-bars, and connecting mechanisms as there are groups of type-wheels, all duplicate of each other) the rock-shaft 92 is rocked, which in turn actuates the segment-gear 99 to rock the inking-bar 101 into the position shown in Fig. 6. The inking-pad on the bar is pressed against the type and the further movement of the hook-plate 93 causes it to slip off of the pin 97 on the rack-lever, and the inking-bar is at once returned to its normal position by the action of the spring 107, secured to the lower end of rack-lever. The platen-lever then impresses the article to be marked, and upon the release of the lever it drops back to its normal position by its own weight, returning through the connecting mechanism the hook-plate to its normal position with its hook in position to engage the pin 97 upon the next operation.

45 The operation of the machine as a whole will be readily understood. Suppose the operator desires to mark a large number of laundry-pieces with the mark "A. M. 47"—some with large type, some small. He first pushes back the hand-crank 71. This rotates the shaft 70, and the drums 72 wind up the chains 66, 67, 68, and 69, and rotate the type-setting cylinders to their full extent until there is an open space under all of the key-lever rods. Holding the hand-crank down, the operator then presses the keys—A in the first group, M in the second, 4 in the third, and 7 in the fourth. These keys are held down by the respective locking-bars and the hand-crank is then released, the tension-springs on the type-setting cylinders carry back the cylinders until they are stopped by the depressed key-rods, and this movement rotates the proper type-wheels of each group 65 through the connecting-gearing to bring the type A on the first wheel, the type M on the second, the type 4 on the third, and the type 7 on the fourth wheel, into the proper printing position, and this is done simultaneously for all the groups of type-wheels that may be provided. Whatever combination of symbols appears at one printing - opening, the same combination will appear at the other printing-openings, the only difference being in the size of the type. The operator then 70 raises the platen-lever by the handles 108, causing the inking-bar to ink the type, then placing the article over the type he presses down the platen and the goods are stamped. When the marking is completed, the operator 75 presses the releasing-key, all of the locking-bars are actuated to release the depressed keys, which by the individual springs are returned to normal, and the type-setting cylinders being thus released are also returned 80 to their normal position by the tension-springs. Should the operator be obliged to leave the machine after the type are set, it will not be possible for any one else to disturb the type already set by striking other 85 keys. If any other keys are depressed or sought to be depressed, the type-rods will either come in contact with the solid portion of the type-setting cylinders, or if any key in advance of the key of any group is depressed the key-rod of this key will have no effect on the particular type-setting cylinder of the group actuated, because the cylinder will still be held in position by the proper key previously depressed. All of the keys must 90 first be released by the releasing-key and the hand - crank actuated before any selected mark can be changed.

Having thus described my invention, what I claim as new, and desire to secure by Letters Patent, is—

1. In a marking-machine for laundry articles, the combination of a plurality of type-setting cylinders, a plurality of similar type-wheels with different-sized type, gearing for connecting the cylinders and wheels, and means for actuating the cylinders to bring the selected type into printing position.
2. In a marking-machine for laundry articles, the combination of a plurality of groups 115 of keys, a type - setting cylinder for each group, mechanism intermediate said keys and cylinders for setting said cylinders, a plurality of similar type-wheels with different-sized type and gearing for connecting the cylinders and wheels whereby the setting of the cylinders will set the type in printing position.
3. In a marking-machine for laundry articles, the combination of a plurality of groups 125 of keys, a type - setting cylinder for each group with notches spirally arranged on said cylinders and pins on the keys to engage said notches and serve as stops for the cylinders, a plurality of similar type-wheels with differ- 130

ent-sized type and gearing for connecting the cylinders and wheels whereby the setting of the cylinders will set the type in printing position.

4. In a marking-machine for laundry articles, the combination of a plurality of type-setting cylinders, a plurality of similar type-wheels with different-sized type the wheels of similar type arranged in groups, the type-wheels of each group mounted loosely on a common shaft with gearing for connecting the wheels of each group and their corresponding cylinders whereby the actuation of the cylinders will bring the selected type into printing position.
5. In a marking-machine for laundry articles, the combination of a plurality of groups of keys, a type-setting cylinder for each group, mechanism intermediate said keys and cylinders for setting said cylinders, a plurality of similar type-wheels with different-sized type, the wheels of similar type arranged in groups, the type-wheels of each group mounted loosely on a common shaft with gearing for connecting the wheels of each group and their corresponding cylinders whereby the actuation of the cylinders will bring the selected type into printing position.
6. In a marking-machine for laundry articles, the combination of a plurality of groups of keys and a type-setting cylinder for each

group with notches spirally arranged in said cylinders and pins on the keys to engage said notches and serve as stops for the cylinders, the cylinders arranged to lock the keys when in normal position, with means for rotating the cylinders to permit operation of the keys.

7. In a marking-machine for laundry articles, the combination of a plurality of groups of keys and a type-setting cylinder for each group with notches spirally arranged on said cylinders and pins on the keys to engage said notches and serve as stops for the cylinders, the cylinders arranged to lock the keys when in normal position, a manually-operated drum with connection therefor to each cylinder for rotating the cylinders to permit operation of the keys and springs for re-rotating the cylinders when released by the drum.

8. In a marking-machine for laundry articles, the combination of a plurality of groups of keys, the keys of each group having horizontal levers arranged in a single row, a locking-bar for each row of key-levers, to prevent the return of any keys actuated, and a single key with connection therefor to each locking-bar whereby the actuation of said key will release all of the locking-bars.

CHESTER W. CANINE.
